US00D669800S

(12) **United States Design Patent**
Takayama et al.

(10) **Patent No.:** US D669,800 S
(45) **Date of Patent:** ** Oct. 30, 2012

(54) **PHYSICAL ACTIVITY MONITOR**

(75) Inventors: **Steven Ryutaro Takayama**, Atherton, CA (US); **Branko Lukic**, Menlo Park, CA (US); **Peter Hsiang Jen How**, Sunnyvale, CA (US); **Bryan Rudolf Grziwok**, Berkeley, CA (US); **Stephen John Senatore**, South San Francisco, CA (US); **Frederick P. Dillon, IV**, San Francisco, CA (US); **Nicole Lee Guthrie**, San Francisco, CA (US); **Denis William Bohm**, Los Altos, CA (US)

(73) Assignee: **HopeLab Foundation, Inc.**, Redwood City, CA (US)

(**) Term: **14 Years**

(21) Appl. No.: **29/390,748**

(22) Filed: **Apr. 28, 2011**

(51) **LOC (9) Cl.** 10-04

(52) **U.S. Cl.** D10/70

(58) **Field of Classification Search** D10/70; 235/105; 377/5, 24.2, 26; 73/514.33, 514.34, 73/510, 513, 527, 530; 702/155, 160, 176, 702/78, 79, 82, 91, 92-95, 104, 116, 141, 702/150, 151, 154, 127, 131, 182, 183, 189, 324/522; 345/165, 156, 905; 600/437, 443, 600/453, 459, 465, 479, 500, 502, 595, 485, 600/481, 483

(57) **CLAIM**

We claim the ornamental design for a physical activity monitor, as shown and described.

DESCRIPTION

FIG. 1 is a top view of the physical activity monitor showing our new design;

FIG. 2 is a bottom view thereof;

FIG. 3 is a front view thereof;

FIG. 4 is a back view thereof;

FIG. 5 is a left view thereof;

FIG. 6 is a right view thereof; and,

FIG. 7 is a perspective view thereof.
